(57) **CLAIM**

I claim the ornamental design for a fuel pump, as shown and described.

DESCRIPTION

FIG. 1 shows a front left perspective view of a fuel pump showing my new design;

FIG. 2 shows a back left perspective view thereof;

FIG. 3 shows a left side view thereof;

FIG. 4 shows a right side view thereof;

FIG. 5 shows a front view thereof;

FIG. 6 shows a back view thereof;

FIG. 7 shows a bottom view thereof; and,

FIG. 8 shows a top view thereof.

The broken lines shown on the drawings are included for the purpose of illustrating unclaimed subject matter and forms no part of the claimed design.
